UNITED STATES PATENT OFFICE.

WILLIAM HUMPHREY PERRIN, DECEASED, LATE OF NEW LISKEARD, ONTARIO, CANADA; BY ARTHUR PERRIN AND GEORGE ALBERT BASSETT, EXECUTORS, OF NEW LISKEARD, ONTARIO, CANADA, ASSIGNORS TO PERRIN SHOCKER MANUFACTURING COMPANY, LIMITED, OF NEW LISKEARD, ONTARIO, CANADA.

SHEAF SHOCKER.

Application filed June 30, 1921. Serial No. 481,565.

To all whom it may concern:

Be it known that we, ARTHUR PERRIN and GEORGE ALBERT BASSETT, both subjects of the King of Great Britain, and both residents

5 of the town of New Liskeard, in the Province of Ontario and Dominion of Canada, are the executors of the estate of the late WILLIAM HUMPHREY PERRIN, who during his lifetime was a resident of the said town 10 of New Liskeard, and who invented certain new and useful Improvements in Sheaf Shockers, of which the following is a specification.

This invention relates to improvements in 15 sheaf shockers, particularly to those of the type in which the sheaves are up-ended as they are discharged from the binder and caught on suitable hooks which rotate in a horizontal plane and are adapted to simultaneously discharge the sheaves in the form 20 of a shock.

One of the objects of the invention are to provide simple improvements in the form of a sheaf gripping hook to enable it to better 25 engage the sheaf and support it in upright position prior to discharge, and such form of hook as may serve as a guide for the sheaf during its discharge.

Further objects are to provide an improved guide means for guiding the sheaf from the binder deck to the hook of the shock forming member.

Further objects still are to provide improved means for engaging the outer portions 35 of the sheaves on the hook prior to discharge and shaping them to form a proper shock.

Further objects still are to provide an improved support for the centre of the sheaves 40 while on the hooks and prior to discharge.

Further objects still are to provide an improved form of slide for guiding the sheaves from the binder deck during up-ending and engagement with the hook.

45 Further objects still are generally to improve and simplify the construction of the device to better adapt the various parts to perform the functions required of them.

It consists essentially of the improved construction hereinafter described in detail in the accompanying specifications and drawings.

In the drawings:

Figure 1 is an elevation of an embodiment of a portion of the binder as used from the 55 stubbleward side.

Figure 2 is a plan view.

Figure 3 is a perspective view of the parts for discharging and up-ending a sheaf.

Figure 4 is a perspective detail, showing 60 one of the supporting hooks and the central support for the same.

Figure 5 is a section on line 5—5 of Fig. 4 partly in elevation of the parts shown in Figure 4.

Figure 6 is a perspective detail of the supporting arms for the guide rope which extends around the sheaves.

Figure 7 is a detail in elevation of the upper end of one of the sheaf supporting 70 arms.

Figure 8 is a sectional elevation, showing one of the supporting arms for the guide rope.

Figure 9 is a perspective detail of one of 75 the hooks.

Figure 10 is a perspective detail of a portion of the discharge mechanism.

Figure 11 is a section on line 11—11 of Fig. 4, showing the supporting and turning 80 mechanism of the shock-forming member.

Figure 12 is a plan view showing certain of the parts shown in Figure 11.

Figure 13 is a perspective detail of the ratchet member of the shock-forming mechanism. 85

Figure 14 is a sectional plan of the cam for the discharge device.

Figure 15 is a perspective view of one of the supporting brackets.

Figure 16 is a perspective view of a portion 90 of the discharge mechanism and of the support for the shock-forming mechanism.

In the drawings, like characters of reference indicate corresponding parts in all 95 the figures.

It may be stated that many parts of the present invention are similar to those shown in my United States Patent No. 1,346,974 granted July 20, 1920.

100 Referring to the drawings:

A indicates the binder deck, below which is operatively mounted a rock shaft 10 provided intermediate of its length with a com-

pressor arm 11 mounted on a shaft 11^a and bent to form a crank 12 connected through a link 13 with a sprocket 14 mounted on a transversely extending tying shaft 15. The sprocket 14 is adapted to actuate the tying mechanism for the binder, the parts of which are of well-known construction in the art and have been clearly shown and described in applicant's Patent No. 1,346,974 for sheaf shocker, patented July 20, 1920.

During its discharge from the binder deck, the sheaf is adapted to be up-ended by mechanism described in detail in the aforesaid patent and including a supporting member 1 having arms 2 and 3 connected to opposite sides thereof, the outer ends of the arms being pivotally connected to the offset delivery arms 4 and 5 intermediate of the length thereof. The shorter ends of the delivery arms are provided with rollers 6 and 7 adapted to co-operate with cams 8 and 9 mounted on the fixed sleeve 30 which surrounds the knotter shaft.

By reference to Figures 3 and 16 in the drawings, it will be seen that the cams 8 and 9 are located on opposite sides of the member 1 and are so arranged relatively to each other that the roller 6 on the arm 4 will become disengaged from the cam 8 prior to the disengagement of roller 7 on the arm 5 from the cam 9 so that the arm 4 is free from the butt of the sheaf, allowing it to drop downwardly while the delivery arm 5 continues on moving in an upward direction on its co-acting cam and, therefore gives the head of the sheaf a greater throw than does the arm 4, thereby facilitating the up-ending of the sheaf into a vertical position.

Located intermediate of the compressor arm 11 and the crank member 12 of the rock shaft 10 is an adjustable crank member 23 provided with a bifurcated end having pivotal engagement with the offset arm 24 of a finger 25, which is adapted to co-operate with a curvilinear cam race 26 operatively supported below the binder deck A adjacent to the said adjustable crank member so that, on actuation of the rock shaft 10, the finger 25 is right over the outer end of the cam race and will be elevated or lowered (see Figure 10).

The butt of the sheaf is designed to be supported by the finger 25 which, during the depression of the compressor arm, is elevated by the rotation of the shaft 10, causing the upper or inner end of the said finger to engage with the edge of the cam surface 26 which causes the finger to be angularly disposed upwardly, thus holding the butt of the sheaf in the desired position. When in this position, the sheaf is also engaged by the Z-shaped compressor arm 66, the upper end of which is pivotally connected to an arm 65 pivoted to a standard 29. The

compressor arm 66 normally extends horizontally and has its outer end bent downwardly at 67 so that it may engage with the butt of the sheaf after it has passed the compressor arm 11 to compress the said butt.

The compressor arm 66 is provided adjacent to its pivoted end with a strap 68 to which one end of a spiral spring 69 is anchored, the other end being secured to an arm 68^a so that, when the arm 66 is displaced on the delivery of the sheaf from the binder deck, the said arm will be returned to its normal position under the action of the spring, (see Figure 15).

The sleeve 30 surrounding the shaft 15 engages and supports one end of the standard 29, the other end of which unites with a similar standard 29^a. The lower end of these standards extends around the tying shaft 15. These standards together support the sleeve 30^a which extends in a stubble-ward direction and constitute part of the supporting mechanism of the shock-forming means. The sleeve 30^a is supported intermediate of its length from the standards by braces 31. The standards 29 and 29^a are united at their upper extremity by a bracket 29^b which is connected to the sleeve 30^a.

The binder deck A is provided at the discharge end and towards the rear thereof with an extension B consisting of a curved guide plate 100 hinged to the binder deck and which is curved upwardly a short distance and has hinged to its upper extremity a supporting plate 101 movement of which is controlled by means of a connecting link 102 having one end 103 bent laterally and engaged with the hinges 104 between the members 101 and 100, the opposite end of the link being pivotally connected to a crank 105 on the knotter shaft 15. The outer end of the supporting plate 101 is rigidly supported by means of a rod 106 having a laterally turned end 107 pivotally connected to brackets 108 on the plate 101, the opposite end of the rod 106 being connected to a brace 109 which extends laterally from the sleeve 30^a being connected thereto by a U-bolt 110.

It will be seen that as the knotter shaft turns, the movement of the crank 105 will swing the hinges of the plate 100 inwardly which will raise the upper end of the plate 100 while depressing the upper end of the plate 101 as hereinafter more fully explained.

The shock forming mechanism C comprises a plate 32 formed on diametrically opposite sides with lugs 32^a which are formed with an upwardly extending projection 33^a adapted to engage the sleeve 30^a above which a plate 35^a is secured by bolts 36^a, the plate 35^a being provided with spaced lugs 111 which support a pin 112 which pivotally retains the hook-shaped end

113 on an arm 114 which extends rearwardly and downwardly, the lower end of which supports a cord 115 which is designed to extend around the sheaves, as hereinafter explained. One end of the cord is fixed to a lug 116 on the arm 114. The cord is looped a distance from the end and is extended through an eye 117 in the lower end of the arm 114, the slack in the cord being taken up by means of a take-up member 118 having an eye 119 at its lower end through which the loop in the cord 115 extends, the free end of the cord being connected to one of the arms 129, as hereinafter described.

15 The upper end of the arm 118 is curved horizontally and supported by one arm of a crank 120, the crank being pivotally connected to a brace 121 secured by suitable bolts 122 to the sleeve 30^a, the crank 120 being adapted to return to normal position when moved therefrom under the action of a spring 123 which extends from one arm of the crank to the brace 121.

20 The plate 32 is provided on its lower face with a downwardly extending boss 34^a to which is connected a vertically disposed and non-rotatable shaft 38. The plate 32 is superimposed on a gear 39 which is rotatably mounted on the shaft 38, being supported by a collar 124 on the shaft which is locked in position by a set screw 125. Intermediate of the boss 34^a and the centre of the gear 39, a cup-shaped tripping member 70 is located and is rigidly secured in position relative to the gear by the spring controlled detent 39^a which engages the serrations 72 in the radial flange 71 on the tripping member. The lower portion of the cup-shaped tripping member is provided 40 with a peripheral pocket 73 adapted to engage with a vertically disposed rod 35 carried by a star-shaped connecting member 48 rotatably mounted on the shaft.

45 Turnably mounted on the upper end of the shaft 38 is a lever 90 provided intermediate of its length with an inverted U-shaped bracket 91 carrying a spring controlled detent 92 designed to engage with the serrations 72 in the flange of the tripping member 70. The outer edge of the lever 90 is connected to a rod 93 which extends to a point adjacent to the driver's seat so that the tripping member may be manually turned when it is found necessary or desirable. The gear 39 is provided with peripherally radially extending lugs 43^a to which the supporting arms 126 are pivotally attached. As shown six arms are provided. Each arm comprises a lever member 127 pivoted intermediate of its length to the lugs 43^a and having at its upper extremity a roller 128 designed at one point in the revolutions of the gear 39 to be engaged by a fixed cam 76 which is separated a distance outwardly from the

gear and designed to swing the upper end of the lever 127 inwardly, thus swinging the lower end outwardly.

5 The lower end of the lever member 127 is connected to a rod 129 which is formed with a laterally turned portion 130 at its lower end extending substantially at right angles to a radius passing through the centre of shaft 38. This extension 130 carries a hook member 131 formed with a laterally extending prong 132 and an intermediate portion 133 which is journalled in eyes 134 on the portion 130 and terminates in an outer hook 135. The prong 132 is considerably longer than the hook 135 and is designed to give considerable support to the sheaf and form a guide for it during the action of discharge.

10 During discharge the hook member 135 is designed to swing downwardly by means of a link rod 136 connected to the prong 132 at its lower extremity and adjustably connected at its upper extremity to a link 137, the opposite extremity of which is connected to the extremity of a lever 138 which is fulcrumed intermediate of its length to a bracket 139 connected to the gear 39, the opposite extremity of the lever 138 being connected to the member 48 by a link 138^a. The adjustable connection between the rod 136 and 15 the link 137 is effected by means of a perforated lug 140 on the link 137 through which the rod 136 extends and is adjustably held by means of nuts 141 on a threaded portion of the rod 136. The arms 129 are 20 retained in normal and innermost position by means of tension springs 142 extending from the rod to the star-shaped member 48.

25 Support is given to the centre of the shock and the formation thereof assisted by 105 means of a central core member 143 mounted on the shaft 38 and formed with a plurality of flutes 144 which are semi-conical in shape, gradually widening towards the bottom whereby the sheaves will be compressed by the flutes at the top but be free to expand at the bottom. The flutes are also deeper at the bottom than at the top.

30 Additional support is given to the sleeve 110 and the shock-forming member by means of a tie rod 145 extending from the pin 112 on the plate 35^a to a rod 146 which is secured to the member 29, the rod 146 being supported by an adjustable tie rod 147 which is connected at its lower extremity 115 to the binder; the adjustable connection in the embodiment illustrated being formed by a laterally turned eye 148 on one portion of the rod which fits a screw-threaded portion formed on another part of the rod 120 being held in adjustable position thereon by a nut 149. By adjusting these nuts, it is possible to adjust the height of the shock-forming member, the arm 146 and the members 29 and 29^a turning about the lower 125 130

end of the members 29 and 29^a which are pivotally supported for this purpose.

Rotatably mounted in the sleeve 30^a is a shaft 41 driven through the gears 42^a and 45^a from the vertical shaft 44^a which is driven from the knotted shaft 15 by the gears 15^a and 16^a, (see Figure 16). The end of the shaft 41 remote from the gears 42^a and 45^a is provided with a gear 40 adapted 10 to mesh with the gear 39 of the shock-forming mechanism C.

In order to further guide the sheaf during upturning, I provide a curvilinear guide rod 150 extending above the member B and 15 substantially parallel therewith, being connected at its upper end to the sleeve 30^a and at its lower end to a portion 150^a of the binder.

In the operation of the invention, the 20 sheaves are delivered in the ordinary operation of the binder against the compressor arm 11 and owing to the rotation of the sprocket 14 by the binder mechanism the rock shaft 10 is actuated through the link 13 to turn the said arm and so allow the sheaf to be delivered to the stubble side of the deck A where the head of the sheaf will rest on the platform B. The bottom of the sheaf is supported by the finger 25, as 30 already explained, and is also engaged by compressor arm 66 and is held in this position until the delivery arms 4 and 5 discharge the sheaf from the binder deck A.

It will be seen that the rollers 6 and 7 35 of the delivery arms 4 and 5 will, on rotation of the member 1, engage with the stationary cams 8 and 9, and, since these cams are arranged in such a manner that the delivery arm 4 is disengaged from the cam 8 40 prior to the disengagement of the delivery arm 5 from the cam 9, the bottom of the sheaf will be allowed to fall slightly downwardly since it is freed earlier from the delivery arm than the head, which will be 45 thrown upwardly by the delivery arm 5, so facilitating the up end of the sheaf.

The up-ending of the sheaf is further assisted by the movement of the member 100 which is moved upwardly and inwardly by 50 the operation of the crank 105 and rod 102; at the same time the outer plate 101 is moved downwardly about the hinges 104, which gives a clearance to the sheaves and permits them to pass by the upper part of the member B. The sheaf, when discharged in an 55 up-ended position, is engaged by one of the hook-members 133 on the arm 129 of the shock-forming mechanism. It will be understood that simultaneous to the operation 60 of the rock shaft 10, rotary motion is transmitted to the shaft 41 on the binder mechanism so that the pinion 40 meshing with the gear 39 causes the shock-forming mechanism C to be rotated so permitting the 65 hook member 133 of each arm 129 to be en-

gaged with a sheaf as it is delivered from the binder deck A, the arm being thrown outwardly in a proper position for this purpose by action of the roller 128 engaging the cam 76.

The inner ends of the sheaves are supported by the core member 143, being held against the same by the arm 129 and hook members 133. The sheaves will also be held in position by the cord 115, the end of 75 which is connected to the arm 129, so that the said cord will extend on the outer side of the sheaves and will be wound around them. When the shock is finally discharged, the slack in the cord will again be 80 taken up by action of the member 118, as previously explained.

When the hook members 133 are all filled, the rod 35 will come opposite to the recess or peripheral depression 73 in the cup-shaped tripping member 70, and the weight of the sheaves on the hook members 133 will cause the star-shaped member 48 to be elevated, actuating the lever 138 and depressing the hooks through the rods 136, so permitting the sheaves to be simultaneously discharged in the form of a shock. During this operation, the flexible member 115 will surround the heads of the sheaves, binding the same together to give the best possible form 95 of shock.

When the machine has reached the end of the cut, it may be that the number of sheaves gathered by the shock-forming mechanism C is not sufficient to form a complete shock 100 and, therefore, will not automatically drop the sheaves before a new cut is started. In order to accomplish this, the driver of the binder operates the link 93 thereby turning the lever 90 above the upper end of the 105 shaft 38; the detent 92 will thus engage with the teeth 72 and rotate the tripping member 70 through a predetermined distance for each movement of the lever until the peripheral pocket 73 engages with the rod 35 110 of the star-shaped member 48, allowing the same to be elevated and so drop the sheaves carried by the hook members 133. The lever 90 being retracted by hand, when necessary, to its original position.

It will be seen that the form of hook members 133 designed is adapted to effectually support two sides of the shock and so hold the same in proper position during formation of the shock. It will be seen also that the flexible member or rope 115 does not drag on the ground as in my earlier patent but the slack is taken up by means of the spring actuated member 118. The grooves or flutes in the core 143 serve to guide the 125 sheaves in dropping in the form of a shock and also to maintain them in proper position during the shock-forming operation. It will also be seen that the member B together with the guide rod 150 forms an ef- 130

fectual guide and slide for each individual sheaf during discharge, and yet the upper part of the member B is moved out of position to give clearance for the movement of each sheaf during discharge.

As many changes could be made in the above construction, and many apparently widely different embodiments of my invention within the scope of the claims, constructed without departing from the spirit or scope thereof, it is intended that all matter contained in the accompanying specification and drawings shall be interpreted as illustrative and not in a limiting sense.

15. What I claim as my invention is:

1. In a sheaf shocker the combination with means for up-ending each sheaf as it is discharged from the binder, shock-forming mechanism adapted to receive each sheaf as it is up-ended and to discharge a plurality of sheaves in the form of a shock, of a guide member adapted to guide the sheaf during up-ending and discharge, and formed with two hinged sections, and means for moving 25 the hinge connecting the two sections.

2. In a sheaf shocker the combination with means for up-ending each sheaf as it is discharged from the binder, shock-forming mechanism adapted to receive each sheaf as it is up-ended and to discharge a plurality of sheaves in the form of a shock, of a hinged guide platform, and means for oscillating the same during discharge of each sheaf.

35. 3. In a sheaf shocker the combination with means for up-ending each sheaf as it is discharged from the binder, shock-forming mechanism adapted to receive each sheaf as it is up-ended and to discharge a plurality of sheaves in the form of a shock, of a hinged guide platform having a hinged upper end member, means for supporting the upper end of the end member, and means for moving the hinge between the two members during discharge of each sheaf.

4. In a sheaf shocker the combination with means for up-ending each sheaf as it is discharged from the binder, shock-forming mechanism adapted to receive each sheaf as it is up-ended and to discharge a plurality of sheaves in the form of a shock, of a hinged guide platform having a hinged upper end member, means for supporting the upper end of the end member, means for moving the hinge between the two members during discharge of each sheaf, the said means comprising a rod having a laterally turned end connected with the hinge, and a crank operatively connected to the rod.

60. 5. In a sheaf shocker the combination with means for up-ending each sheaf as it is discharged from the binder, shock-forming mechanism adapted to receive each sheaf as it is up-ended and to discharge a plurality of sheaves in the form of a shock, of a

hinged guide platform adapted to guide the sheaf during discharge, means for oscillating the guide platform, and a guide rod spaced a distance above the guide platform.

6. In a sheaf shocker the combination with means for up-ending each sheaf as it is discharged from the binder, shock-forming mechanism adapted to receive each sheaf as it is up-ended and to discharge a plurality of sheaves in the form of a shock, of a curvilinear guide platform extending from the binder deck adapted to guide each sheaf during discharge, and a curvilinear guide rod spaced from the guide platform and above the same.

7. In a sheaf shocker of the character described, a sheaf engaging hook formed of a rod having a straight intermediate portion, a laterally extending prong at one end of the intermediate portion and a hook shorter than the prong at the other end.

8. In a sheaf shocker of the character described, a shock-forming member, a pivoted arm on the shock-forming member having a lower laterally turned end, and a hook member pivotally mounted in the laterally turned end.

9. In a sheaf shocker of the character described, a shock-forming member, a pivoted arm on the shock-forming member having a lower laterally turned end, and a hook member pivotally mounted in the laterally turned end, said hook member being formed with a prong at one end and a hook at the opposite end.

10. In a sheaf shocker of the character described, a sheaf supporting arm, a hook member pivotally mounted in the arm, forming a prong at one end and a hook at the opposite end, and means for actuating the hook member.

11. In the sheaf shocker of the character described, a sheaf supporting arm having a laterally turned end formed with a plurality of eyes thereon, a hook member pivotally mounted in the eyes, and means for actuating the hook member.

12. In a sheaf shocker of the character described, a rotary shock forming member, a plurality of arms thereon, a pivoted hook member on each arm, a vertical rock shaft, a vertically movable member on the shaft, a plurality of levers each fulcrumed intermediate of its length to the shock forming member, means for connecting the outer ends of the levers to the hook members, and means for connecting the inner ends of the levers to the vertically movable member.

13. In a sheaf shocker of the character described, a rotary shock-forming member, a plurality of arms thereon, a pivoted hook member on each arm, a vertical rock shaft, a vertically movable member on the shaft, a plurality of levers, each fulcrumed inter-

mediate of its length to the shock forming member, means for connecting the outer ends of the levers to the hook members, means for connecting the inner ends of the 5 levers to the vertically movable member, means for moving the arms outwardly, and spring means for retaining the arms in innermost position.

14. In a sheaf shocker of the character 10 described, a rotary shock-forming member, a plurality of arms thereon, a pivoted hook member on each arm, a vertical rock shaft, a vertically movable member on the shaft, a plurality of levers, each fulcrumed in- 15 termediate of its length to the shock forming member, means for connecting the outer ends of the levers to the hook members, means for connecting the inner ends of the levers to the vertically movable member, 20 and means for adjusting the connection between the levers and the hook members.

15. In a sheaf shocker of the character described, the combination with a rotary sheaf-shocking member having a plurality 25 of sheaf supporting arms and a central sheaf support, of a flexible member adapted

to extend around the outside of the sheaves, a supporting rod connected to one end of the flexible member, and means for taking up the slack in the said flexible member. 30

16. In a sheaf shocker of the character described, the combination with a rotary sheaf-shocking member having a plurality of sheaf supporting arms and a central sheaf support, of a flexible member adapt- 35 ed to extend around the outside of the sheaves, a supporting rod connected to one end of the flexible member, means for tak- ing up the slack in the said flexible mem- ber, the said means comprising a rod and a spring actuated crank operatively con- 40 nected to the rod.

In witness whereof we have hereunto set our hands in the presence of two witnesses.
